WEB-FEEDING MECHANISM.

Application filed November 2, 1923. Serial No. 672,233.

The invention relates to an improvement in web feeding mechanisms.

The object of the invention is to produce a web feeding mechanism having provision for varying the amount of web fed during a given interval or period of actuation of the mechanism by predetermined increments or decrements. The web feeding mechanism to which the improvements of the invention are applied is provided with a pair of feed rolls adapted to engage the web between them and with means for advancing the web a predetermined length during each actuation of the rolls when the rolls are actuated intermittently, or during a given period of actuation of the rolls when the rolls are driven constantly. The improvements of the invention provide such a web feeding mechanism with means whereby the length of web fed at each periodic or other operation of the feed rolls may be increased or decreased by predetermined amounts.

For the purpose of illustrating the principles of the invention it will be described as used for the purpose of feeding a web of printed foil or paper to a wrapping machine. It is assumed that the problem is to enclose an article in a wrapper having printed matter on it and that it is desired to have the printed matter occupy substantially the same place on all the articles. Heretofore it has been the common practice to supply such wrappers to the wrapping machine as separate sheets. The desideratum is, however, to feed the printed wrappers to the wrapping machine from a web or roll. The difficulty in supplying the wrapping machine with wrappers from a web or continuous roll lies in the fact that the printed impressions on the web are not always the same distance apart; and also because it is difficult, if not impossible, to synchronize the feeding gears of the wrapping machine with the feeding gears of the printing press which prints the web. Hence, when it has been attempted heretofore to supply printed wrappers to a wrapping machine from a web or roll the printed matter has not occupied the proper place on the article wrapped. For this reason it is customary, as pointed out above, to feed printed wrappers to wrapping machines as separate sheets when it is desired that the printed matter always occupy sub-

stantially the same position on the wrapped article.

By the use of the improved web feeding mechanism of the present invention printed wrappers may be supplied to a wrapping machine from a web or roll and the printed matter on the wrapper will always occupy substantially the desired position on all the articles. The means by which this end is attained comprise a driven member connected with the feed rolls, means for actuating the driven member in one direction to advance the web a predetermined length, and means operative to increase or decrease the amount of actuation of the driven member in order to increase or decrease by a predetermined amount the length of web fed. More specifically this means comprises two pairs of planetary gears operatively connected and arranged to have differential movements, and means for effecting a planetary movement of the gears in one direction to increase the amount the feed rolls are turned and in the opposite direction to decrease the amount the feed rolls are turned. The invention is more fully described hereinafter and is particularly pointed out in the appended claims.

The preferred form of the invention is illustrated in the accompanying drawings in which Fig. 1 is a side elevation of the improved web feeding mechanism; Fig. 2 is a plan of the parts shown in Fig. 1; Fig. 3 is a horizontal section, on an enlarged scale, through the system of planetary gears; Fig. 4 is a section taken along the line 4-4 of Fig. 1, showing certain parts in plan; Fig. 5 is a section taken along substantially the line 5-5 of Fig. 1; Fig. 6 is a detail view of a portion of the ratchet wheel and its detent; and Fig. 7 is a diagrammatic view of the driving planetary gears to illustrate the principle of the increase and decrease of the amount of rotation of the gear connected with the feed rolls.

The improved web feeding mechanism, as illustrated in the drawings, comprises a pair of feed rolls 10 and 11 mounted on shafts 12 and 13 journaled in the frame 14 of the machine to which the web feeding mechanism is applied. The feed rolls are adapted to engage between them the web 15 which is supplied from a roll not indicated in the drawings. When the feed rolls have been

turned to feed forward a predetermined length of web the blades 16 are actuated from the machine to which the mechanism is applied to sever the amount of web which the rolls have delivered by their last actuation, or during a definite period of operation depending upon whether the rolls are intermittently or constantly driven. Throughout this description it will be assumed that the mechanism which actuates the feed rolls is driven intermittently, although it will be understood that the improvements of the invention are equally well adapted for use in connection with a mechanism which is driven constantly and feed rolls which operate constantly to feed forward the web or tape from which the wrappers are cut off. The shaft 13 on which the feed roll 11 is mounted is provided with a sprocket wheel 17 by which the roll is turned in a counter-clockwise direction. The feed roll 10 is turned in a clockwise direction to cooperate with the roll 11 in feeding forward the web and for this purpose the shaft 13 is provided with a gear 18 which meshes with a gear 9 of equal size mounted on the shaft 12 which carries the roll 10.

The means for driving the feed rolls to advance the web a predetermined length comprise two pairs of planetary gears, a pair of driving gears and a pair of driven gears. The driven member 19 of the pair of driven gears is loosely mounted on a shaft 20, one end of which is journaled in the frame 14 and the other end of which is journaled in the frame 21. On the hub of the gear 19 is fixed a sprocket wheel 22 which is connected with the sprocket wheel 17 by means of a chain 23. The driving member 24 of the pair of driven gears is fixed on one end of a pin 25 fulcrumed in the rim of a worm gear 27 loosely mounted on the shaft 20. The pair of driving gears 29 comprises a driving gear 29 fixed on the shaft 20 and a driven gear 30 fixed on the other end of the pin 25. Thus the driven member of the second or driving pair of planetary gears is rigidly connected with the driving member of the first or driven pair of planetary gears; and the driving member of the second pair of gears is fixedly mounted on the shaft 20, whereas the driven member of the first pair of gears is loosely mounted on the shaft 20. Consequently when the shaft 20 is actuated, the gear 19 is driven to turn the feed rolls; and inasmuch as the gear 19 is loosely mounted on the shaft, it may have a movement relative to the shaft. This construction is availed of to impart movements to the gear 19 other than those imparted it from the gear 29, so that the feed of the web may be increased or decreased when that is necessary.

The shaft 20 is driven from the shaft 32 journaled at its opposite ends in the frames 14 and 21. On the shaft 32 is mounted a sprocket wheel 33 over which passes a chain 34 connected with a source of power not indicated in the drawings. Also fixed on the shaft 32 is the driving member 35 of a Geneva gear construction, the driven member 36 of which is fixed on a shaft 37 journaled in the frames 14 and 21. The member 36 is provided with four radial slots 38 adapted to receive the rolls 39 carried by the driving member 35. The arc-shaped piece 40 of the member 35 is adapted to engage with the arc-shaped depressions 41 in the periphery of the driven members 36 to hold the shaft 37 and the parts between it and the feed rolls stationary while the blades 16 are being actuated to sever the length of wrapper which has been fed forward. On the outer end of the shaft 37 is mounted a gear 43 which drives the gear 44 mounted on the outer end of the shaft 20 through the idler gear 45. The direction of rotation of the various parts described above are indicated by the small arrows on Figs. 1 and 2.

The turning of the feed rolls 10 and 11 from the shaft 32 will be clearly understood by following the movements of the shafts and gears between shaft 32 and the feed rolls. If now the pitch diameter of the gears 43 and 44 is synchronized exactly with the spacing of the printed matter on the web, the web will be advanced at each actuation of the shaft 37 a length exactly equal to the spacing of the printed matter. In such case it would only be necessary to pull the web forward until one section of printed matter thereon is in proper alignment with the wrapping or other devices and thereafter the operation of the feeding mechanism would deliver the printed sections of the web to the same position. However, it is seldom that it is possible to synchronize the gears of the feeding mechanism with the spacing of the printed matter on the web. Moreover, the spacing between the sections of printed matter on the web is often not uniform, particularly if the web is composed of foil. Consequently it is necessary to provide the web feeding mechanism, constructed as described above, with means by which the amount the feed rolls are turned may be either increased or decreased according to whether the spacing of the printed matter on the web is either greater or less than the length of web fed at each actuation of the feeding mechanism.

The amount the feed rolls are turned may be either increased or decreased by imparting a planetary motion to the gears 30 and 24 about the gears 29 and 19, respectively. If the gears 30 and 24 are moved in a clockwise direction about the gears 29 and 19 during the regular web feeding movements of the gears, the amount the feed rolls are

turned will be increased. And if on the other hand, the gears 30 and 24 are moved in a counter-clockwise direction about the gears 29 and 19 during the regular web feeding movements of the gears, the amount the feed rolls are turned by the feeding mechanism will be decreased. By shifting the fulcrum of the gear 30 in a direction opposite to the direction in which the teeth of the gear 29 are moving the amount of turning imparted to the gear 30 by the gear 29 is increased and hence the amount the feed rolls are turned is increased. On the other hand, by shifting the fulcrum of the gear 30 in the direction in which the teeth of the gear 29 are moving, the amount of turning imparted to the gear 30 by the gear 29 is decreased and hence the amount the feed rolls are turned is decreased. This mode of operation will be made clear from a consideration of the diagram shown in Fig. 7.

It is assumed that gear 30 normally occupies the position, with respect to gear 29, shown at position X and that when the shaft 20 is actuated the rotation imparted to gears 29 and 30 advances the web the desired length. If now it is desired to increase the length of web fed during this rotation of the gears 29 and 30, the gear 30 is shifted from position X to another position indicated by the dotted lines Y. The length of arc traveled by the fulcrum of the gear 30 about the axis of the shaft 20 during the rotation of the gears 29 and 30 determines the increment of feed of the web. If gear 29 contains twice as many teeth as gear 30, tooth A on gear 29 will always engage tooth A' on gear 30 at the point indicated in full lines while gear 30 occupies its assumed normal position. If now gear 30 is shifted to position Y while both gears are rotating tooth A of gear 29 will engage tooth A' of gear 30 sooner, and gear 29 will turn gear 30 while tooth A travels from its point of actual engagement with tooth A' to the point where it normally engages tooth A'. Thus during the actuation of shaft 20 gear 29 imparts proportionally that much more rotation to gear 30.

On the other hand, if during the actuation of the shaft 20 gear 30 is shifted from position X to the position indicated by the dotted lines Z the decrease in the amount of web fed will be proportionate to the arc traveled by the fulcrum 25 of gear 30. In this case it will be clear that before tooth A of gear 29 engages tooth A' of gear 30 it will have traveled inoperatively through the space traversed by the fulcrum of the gear 30 in reaching position Z. Hence gear 29 will have failed to turn gear 30 as much as when gear 30 occupies its normal position, and consequently the feed rolls 10 and 11 will be turned that much less and will not deliver the normal length of web.

The means for imparting the planetary motions to the gears 30 and 24 about the gears 29 and 19, respectively, comprise the worm gear 27 in which the pin 25 is fulcrumed and a worm 47 which meshes with the teeth of the gear 27. The worm 47 is fixed on a shaft 48 journaled in the ends of the brackets 49 and 50 secured to the frame 14. On one end of the shaft 48 is mounted one member 52 of a pair of miter gears, the other member 53 of which is mounted on a shaft 54 journaled in the frames 14 and 21. The shaft 54 may be turned in either direction to rotate the worm gear 27 in either direction, and for this purpose a ratchet device is mounted on the forward end of the shaft 54. The ratchet device consists of a ratchet wheel 56 mounted loosely on the shaft 54, a plate 57 the hub of which is secured to the shaft 54, and a plate 58 which frictionally presses the ratchet wheel 56 against the plate 57 by means of the bolts 59 and springs 60 (Fig. 5). The actuating member of the ratchet device consists of a spring-pressed pawl 62 mounted in the outer end of the arm 63, the hub 64 of which is loosely mounted on the shaft 54. The pawl is provided with a handle 65 by which the detent may be disengaged from the ratchet wheel. The ratchet wheel engaging end of the detent is of usual construction and the outer end of the arm 63 is slotted to receive a rib 66 on the handle 65 to hold the pawl in operative relation with the ratchet wheel. By withdrawing the rib from the slot and turning the handle to permit the rib to rest on the outer end of the arm 63, the ratchet wheel and the parts connected with it may be turned freely in either direction. The ratchet device is provided with the frictional connection between the ratchet wheel 56 and the plate 57 so that the shaft 54 and the parts connected with it may be turned in either direction while the pawl is in engagement with the ratchet wheel. The shaft 54 and the parts connected with it are turned manually by means of the handle 67 fixed on the forward end of the shaft 54. The parts may also be turned manually by manipulating the handle 68 mounted on the free end of the shaft 48.

The arm 63 is oscillated to turn the ratchet wheel 56 in either direction from the shaft 32 and for this purpose an arm 69 is fixed on the forward end of the shaft 32 and is connected by a link 70 with an arm 71 secured to a pin 72 fulcrumed in the frame 14 (Fig. 4). On the forward end of the pin 72 is fixed a device for regulating the amount of oscillation of the arm 63, and so the amount the worm gear 27 is turned in either direction. This regulating device comprises an arm 74 fixed on the pin 72 and a nut 75 pivotally connected by means of the link 76 with the arm 63. The nut 75

is in threaded engagement with a screw 77 journaled in the offset ends of the arm 74 as shown in Fig. 4. To prevent the nut 75 from turning as it travels along the screw 77 to adjust the amount of oscillation of the arm 63, the nut 75 is provided with a pin 78 loosely engaged in a slot 79 cut longitudinally in the arm 74. One end of the screw 77 is provided with a handle 80 by which it 10 may be turned to shift the position of the nut 75 and so adjust the amount of oscillation of the arm 63. To hold the nut 75 in adjusted position the outer surface of the offset end 81 of the arm 74 is provided with 15 a series of depressions 82 adapted to receive a series of balls 83 which are spring-pressed into the depressions. When the handle 80 is turned the balls 83 are received in holes in the hub of the handle to permit the screw 77 20 to be turned.

It will be obvious that by shifting the nut 75 along the screw 77 the amount of oscillation of the arm 63 will be varied. The arm 74 oscillates on the pin 72 as a 25 center and the nearer the nut 75 is to the pin 72 the less the oscillation of the arm 63 will be, and conversely, the farther away from the pin 72 the nut 75 is, the greater will be the amount of oscillation of the arm 30 63. And, of course, the amount of travel of the worm gear 27 in either direction at each actuation of the web feeding mechanism will depend upon the amount of oscillation of the arm 63.

35 When a fresh web is placed in the web feeding mechanism and the spacing between the printed matter on the new web is different from the spacing between the printed matter on the webs previously operated on, it is first necessary to change the gears 43 and 44, substituting for them other gears which will most nearly give the required amount of rotation to the feed rolls to feed 40 forward the requisite length of web. The 45 idler gear 45 is, as is usual in such situations, so mounted that it may be moved to adjust itself to the gears 43 and 44, whatever their size. If the new gears 43 and 44 are synchronized exactly with the gears 50 which fed the web through the printing press and the web is not stretched or contracted, the web feeding mechanism will deliver the requisite lengths of wrapper with 55 the printed matter properly positioned. If, however, the length of web advanced at each 60 operation of the web feeding mechanism is less than the spacing between the centers of two adjacent groups of printed matter, the pawl 62 will be set to cause the worm wheel 65 27 to be turned in a clockwise direction and the nut 75 will be set at such a distance from the center of the pin 72 to impart to the arm 63 an oscillation sufficient to turn the worm gear 27 enough to cause the requisite increase of rotation to be imparted to

the feed rolls to deliver a proper length of web. On the other hand, if the web feeding mechanism is feeding forward with each actuation too great a length of web, the operative reverses the position of the detent 62 70 so as to cause the worm wheel 27 to be turned in a counter-clockwise direction. Usually several lengths of wrapper will be cut off from the web before the nut 75 is properly adjusted. When it is found that 75 the various parts of the web feeding mechanism are properly adjusted to deliver the requisite length of web at each actuation of the mechanism, the machine to which the web feeding mechanism is applied is started 80 in operation. If the spacing of the printed matter on the web is exactly uniform, the requisite lengths of web with the printed matter properly positioned thereon will be severed by the cutters 16. But the spacing 85 of the printed matter on the webs is seldom uniform for a number of reasons, and consequently it is necessary for the operative to ascertain from time to time whether the printed matter on the severed wrappers occupies the proper position. If it does not, the operative will turn the shaft 48 by means of the handle 68 so as to turn the worm wheel 27 in either a clockwise or a counter-clockwise direction, according to the position 90 of the printed matter on the wrapper. The operative does this while the web feeding mechanism is in operation. The same effect can be produced by manipulating the handle 67. 100

Having thus described the invention what I claim as new is:—

1. A web feeding mechanism having in combination, a pair of feed rolls adapted to engage a web between them, a shaft, a pair of planetary gears the driven member of which is loosely mounted on the shaft and is connected with the feed rolls, a second pair of planetary gears the driving member of which is fixed on the shaft, a second shaft 105 constantly driven, means through which the second shaft imparts an intermittent motion to the first shaft, means for supporting the driving member of the first pair of gears and the driven member of the second pair of gears so that they will travel about their companion gears respectively, and, means driven from the second shaft for imparting a rotary motion about the first shaft to the gear supporting means. 110

2. A web feeding mechanism having in combination, a pair of feed rolls adapted to engage a web between them, means including a system of planetary gears for driving the feed rolls to advance the web a predetermined length, and a ratchet mechanism connected with the planetary gears for increasing and decreasing the amount of actuation of the web advancing means to cause a greater or less length of web to be ad- 125 130

vanced during the movement of the feed rolls.

3. A web feeding mechanism having in combination, a pair of feed rolls adapted to engage a web between them, a gear connected with the feed rolls, means for driving the gear to actuate the feed rolls to advance the web a predetermined length, said gear driving means including a second gear mounted to have a planetary motion about the axis of the first gear, and means including a ratchet mechanism actuated at each cycle of operation of the gears for imparting a planetary motion to the second gear in either direction to increase or decrease to a predetermined extent the amount of web advanced by the feed rolls.

4. A web feeding mechanism having in combination, a pair of feed rolls adapted to engage a web between them, a set of planetary gears for actuating the feed rolls to advance the web a predetermined length, means for driving the planetary gears, and a ratchet mechanism connected with the planetary gears and actuated at each cycle of operation thereof for increasing and decreasing to a predetermined extent the amount of web advanced by the feed rolls.

5. A web feeding mechanism having in combination, a pair of feed rolls adapted to engage a web between them, a shaft, a pair of planetary gears, the driven member of which is loosely mounted on the shaft and is connected with the feed rolls, a second pair of planetary gears, the driving member of which is fixed on the shaft, a second shaft constantly driven, means through which the second shaft drives the first shaft intermittently, a worm gear loosely mounted on the first shaft for supporting the driven gear of the second pair of gears and the driving gear of the first pair of gears, and ratchet means actuated from the second shaft for turning the worm gear in either direction by predetermined amounts.

6. A web feeding mechanism having in combination, a pair of feed rolls adapted to engage a web between them, a shaft, a pair of planetary gears, the driven member of

which is loosely mounted on the shaft and is connected with the feed rolls, a second pair of planetary gears, the driving member of which is fixed on the shaft, a second shaft constantly driven, means through which the second shaft drives the first shaft, a worm gear loosely mounted on the first shaft for supporting the driven gear of the second pair of gears and the driving gear of the first pair of gears, and ratchet means including a ratchet mechanism for turning the worm gear in either direction to a predetermined extent.

7. A web feeding mechanism having in combination, a pair of feed rolls adapted to engage a web between them, a set of planetary gears for actuating the feed rolls to advance the web a predetermined length, and means connected with the planetary gears actuated at each cycle of operation thereof for positively controlling by predetermined amounts the actuation of the feed rolls.

8. A web feeding mechanism having in combination, a pair of feed rolls, a set of planetary gears comprising a driven member connected with the feed rolls, a driving member, means for actuating the driving member, a movable third member normally stationary for controlling the amount of actuation imparted to the driven member by the driving member, and means operating at each cycle of operation of the gears for positively actuating the third member by predetermined amounts.

9. A web feeding mechanism having in combination, a pair of feed rolls, a set of planetary gears comprising a driven member connected with the feed rolls, a driving member, means for actuating the driving member, a third member for controlling the amount of actuation imparted to the driven member by the driving member, and a ratchet mechanism operating at each cycle of operation of the gears for actuating the third member.

MILFORD B. FERGUSON.
